PRIME MOVER

Peter James McAndrews, Jamaica, N. Y.

Application December 3, 1941, Serial No. 421,476

12 Claims. (Cl. 60—41)

(Granted under the act of March 3, 1883, as amended April 30, 1928; 379 O. G. 757)

The invention described herein may be manufactured and used by or for the Government for governmental purposes, without the payment to me of any royalty thereon.

This invention relates to prime movers and particularly to an improved compound engine incorporating the best features of a steam reciprocating engine, an explosive engine and a steam turbine.

It is the primary object of this invention to provide a compound engine having a high thermal efficiency in which normally wasted heat is utilized to produce added power.

An object of this invention is to reduce the water rate per horse power by the use of exhaust steam, reheated, in a turbine engine.

A further object of this invention is a reduction in the weight of the elements of the explosive section of a prime mover by using high cooling temperatures whereby relatively low compression pressure is required for ignition.

Another object of this invention is a prime mover in which the necessity of air drums and air compressors for starting is eliminated by the utilization of what is, in effect, a simple reciprocating steam engine for producing the necessary compression pressure.

Still another object of this invention is to obtain an improvement in the heat balance between the elements of my improved prime mover by the interchange of heat and by the use of jacket cooling by circulating fluid at temperatures approximating 400° F.

Other objects of this invention are to improve the evaporation per pound of fuel used in a steam boiler separately fired; the utilization of explosive engine exhaust to increase feed water temperature; and the securing of preheated air for combustion and scavenging by the use of a simple trunk-type piston and cylinder operating as a crosshead and guide between piston and connecting rod.

These and other objects and advantages of my improved prime mover will be apparent upon consideration of the following description and the accompanying drawings which illustrate an embodiment of my conception.

For the purposes of simplicity in description and for a clearer understanding of my invention I have shown the explosive engine as a Diesel unit. It will be clear that the advantages of my invention will be achieved as well by any other type of explosive engine. I have also shown but a single steam-Diesel unit but it is apparent that any desired number of these units may be used in connection with a suitable crankshaft without departing from the spirit of my invention.

While I have not described the boiler used in conjunction with my improved prime mover in particularity, I prefer to use a boiler of the type

disclosed in my copending application Serial Number 421,475 filed December 3, 1941.

In the drawings, Fig. 1 is a plan view of my improved prime mover;

Fig. 2 is a view, partly in cross section, along the lines 2—2 of Fig. 1;

Fig. 3 is an end view of the prime mover connected to a suitable boiler system;

Fig. 4 is an elevation of the prime mover;

Fig. 5 is a cross section along the lines 5—5 of Fig. 1;

Fig. 6 is a cross section along the lines 6—6 of Fig. 1;

Fig. 7 is an enlarged view in cross section of the air scavenging valve;

Fig. 8 is an enlarged view in cross section of the check valves;

Fig. 9 is a side elevation of the reversing sleeve mechanism; and

Fig. 10 is a top elevation of Fig. 9.

Referring particularly to Figs. 1 and 2, it will be seen that my improved prime mover consists essentially of an opposed piston section and a steam turbine section. The opposed piston section operates as a combined simple reciprocating steam engine and a Diesel engine. The steam turbine section is adapted to be operated by the exhaust steam from the reciprocating engine.

In the figures the numeral 1 refers to a cylinder of the steam-Diesel unit having radially extending surfaces 15 and in which pistons 2 operate on the two-stroke principle. Pistons 2 are connected by means of piston rods 3 to operating crosshead compressors 4 which are free to move in compressor cylinders 5. The compressors 4 are connected to the crankshafts 7 by means of connecting rods 6. On the crankshafts 7 are mounted pinion gears 8 which drive the main gear 9 to which the main shaft 10 is connected. Thrust bearing 11 is provided to house the main shaft 10. Forward turbine 12 and reverse turbine 13 are connected to the crankshafts 7.

Means for supplying air to the cylinder for combustion and scavenging are provided by the following arrangement. Air intake check valves 14 (see Fig. 8) supply air to the compressor cylinders 5. Air compressed in the cylinders 5 flows through air supply pipes 15 through check valves 16 to air storage chest 17. Air from the storage chest 17 passes through scavenging valve 18 (see Fig. 7). The semi-burned gases are exhausted through exhaust ports 19, uncovered by the pistons 2 and pass by means of gas pipe 20 to the furnace 21 of the boiler where combustion is completed. The scavenging valve 18 is cam operated by camshaft 22 connected to the drive shaft 19 by suitable gearing 23. The cam operating the scavenging valve 18 will open and close the valve in the same ratio on either side of dead

center eliminating the necessity for reversing mechanism at this point.

Referring to Fig. 3, the following path is provided for the steam: From the steam drum 24, and above the water level, steam supply pipe 25 leads to the throttle valve 26. The steam is then divided and enters the crank end of the cylinder 1 through intake valves 27. The steam exhausts through valves 28 into turbine supply pipe 29. Valve 30 is provided to control the admission of steam to turbine 12 and valve 31 to control the admission of steam to turbine 13. Steam exhausts from the turbines into condenser 32, cooling water for which is supplied by pump 33. The condensate is removed by condensate pump 34 and is pumped back to the boiler by feed pump 35.

The following path is provided for the circulation of cooling water: From the steam drum 24, and below the steam level, supply pipe 36 leads to the jacket 37 of cylinder 1. The jacket 37 consists of tubular sheet steel shrunk onto the cylinder 1. The circulating water is also fed to jackets 38 about the compressor cylinders 5. Collection pipes 39 at the lower level of the cooling jackets feed the circulating water to the mud drums of the boiler.

Referring to Figs. 4 and 5, the intake and exhaust valves 27 and 28 are actuated by cam rods 41 which are driven from camshafts 42. Camshafts 42 are driven from the crankshafts 7 by chains 43.

Referring to Fig. 6, fuel oil for the Diesel operation is supplied by a suitable feed pump 44 attached to either of the camshafts 42. The injection of oil into the cylinder 1 through fuel supply pipe 45 and injection valve 46 is controlled by an added cam 47 on the camshaft 42. Injection valve 46 is operated from cam 47 through the Bowden wire 79.

The operation of my improved prime mover is as follows: The boiler and engine water circulating jackets 37 and 38 are filled with water to the steaming level of the boiler. The engine jackets, being on a lower horizontal plane, are pressed full and this arrangement assures circulation by thermo-syphon action through supply pipes 36 and collector pipes 39. Steam is then raised by firing the boiler and the steam turned through the steam side of the reciprocating unit by opening the throttle valve 26, permitting steam to flow to the intake valves 27. Steam entering the crank ends of the cylinder 1 causes pistons 2 to move towards each other. This movement of the pistons 2 causes a corresponding movement of the piston rods 3, compressor pistons 4, connecting rods 6 and crankshafts 7. Steam is exhausted through exhaust valves 28 into turbine supply pipe 29 where turbine valves 30 and 31 divert the exhaust steam to ahead turbine 12 or reverse turbine 13 as the direction of engine rotation requires, one turbine being used only in each direction, the idle turbine serving, meanwhile as a flywheel.

As the steam pistons 2 move from the crank end to the head end of the stroke the clearance between the piston heads is closed setting up compression, and at approximately top stroke, fuel is forced through injection valve 46 from the fuel pump 44 which is operated from the camshaft 42. When ignition takes place the pistons 2 are moved toward the crank end completing the combustion power stroke. Nearing the end of the internal combustion power stroke ports 19 are uncovered by pistons 2 allowing the gases of combustion to be discharged under the

action of scavenging air into gas pipe 20. From gas pipe 20 the gases exhaust directly into the boiler furnace 21 to mix with boiler furnace combustion gases and complete combustion of the unburned parts of the engine exhaust usually present in the exhaust of oil engines, and especially those of high speed.

The accumulated heat of pistons 2, together with radiated heat from water jacket 37 eliminates the temperature losses of expanding steam as experienced in the conventional type of reciprocating engine. The remainder of the heat of combustion is radiated through the radial extended surfaces 75 of the cylinder wall to the jacket water adding heat and assisting evaporation of water in the boiler. As the compressor pistons 4 move from the crank end of the cylinder 5 the air above their faces will be compressed and will flow through supply pipes 15, through check valves 16 and into the air storage chest 17. The air for scavenging is admitted from the air storage chest by valve 18 actuated by camshaft 22 driven off the main shaft 10. The air is preheated by means of the heat radiated from the fluid circulating in the compressor jackets 38. When scavenging is completed the admission of steam to the opposite sides of pistons 2 reduces the radiated heat losses of the air under compression in the internal combustion cylinder. This, with the heat of compression, causes the air to attain a sufficiently high temperature to promote ignition, without the necessity of a high compression ratio.

The pinion gears 8 and the main gear 9 may be of any suitable ratio to obtain the desired shaft speed.

The scavenging valve timing will be maintained by direct gearing 23 with the main shaft 10. The cam operating the valve will open and close the valve in the same ratio on either side of bottom center of the crankshaft during the exhaust period. Reversing mechanisms will therefore be unnecessary at this point, and the scavenging and charging function will prevail on this timing without regard to the direction of rotation of the engine.

The fuel injection pump will be in the same degree of advance or lead on either side of top center of the crankshaft and will follow the fuel oil injection function without regard to the direction of rotation of the engine, also eliminating the necessity of a reversing mechanism at this point.

The direction of rotation where the reversing feature is required will be controlled fully from the steam-operating side of the pistons 2 by manipulation of a sliding sleeve-reversing mechanism on the camshafts 42. Such a reversing mechanism is shown in U. S. Patent No. 2,018,790, granted to J. S. Keen, on October 29, 1935, and as may be seen from a consideration of Figs. 9 and 10 consists of a sliding sleeve 80 keyed to the grooves 81 in the shaft 42 whereby the forward or reverse movement of the operating arm 82 rotates the shafts 42 and their associated cams 180 degrees.

Any of the customary methods of supplying oil to the wrist pins 76 may be used. The oil which splashes off wrist pins 76 and the connecting rods 6 will lubricate the compressor pistons 4 and the oil that passes the rings 77 of the compressor pistons 4 will, due to the high temperature of the compressor cylinder walls, become vaporized and be entrained with the scav-

enging air, effectively lubricating the internal combustion cylinder 1.

It will be seen that by my invention I have provided an improved prime mover in which boiler water is circulated through the engine jackets, whereby the combustion cycle is improved in the one case and the water rate in the other. The modification of the wide range of temperatures now experienced in practice reduces the unequal thermal stresses present in such engines. By my invention I obtain a recovery of the heat now lost in the exhaust as well as the loss of power through back pressure in the exhaust now being experienced through the necessity of operating internal combustion engines with a muffler as against the arrangement herein set forth, whereby the internal combustion engine will exhaust inside of a boiler jacket where the operating pressure will actually be lower than atmospheric pressure and the great number of tubes staggered in the path of the exhaust gases will eliminate the necessity of a muffler. Similarly, the heat of radiation which is useless in present internal combustion is utilized in heating the steam from the steam-Diesel unit whereby its energy may be added to the residual energy in the steam and such normally wasted steam used to drive an added mechanism supplying useful power to the drive shaft.

While I have illustrated but a single embodiment of my invention, it is obvious various modifications may be made without departing from the spirit of the invention and I do not wish to be limited to the particular arrangements and assemblies shown.

Having described my invention, what I claim as new and wish to secure by Letters Patent is:

1. In a prime mover for operating a drive shaft, the combination of a double acting engine having a pair of opposed pistons, means to admit steam pressure to actuate said pistons for a portion of their stroke and internal combustion means to return said pistons, a pair of crankshafts driven by said pistons, dual turbines, one of each of said turbines connected to one of each of said crankshafts, means to drive only one of either of said turbines by the entire exhaust steam discharged from said double acting engine, with the particular turbine being driven depending on the forward or reverse running of said engine and the undriven turbine having a flywheel effect, and means connecting said crankshafts to said drive shaft.

2. A prime mover, according to claim 1, including in addition, a boiler, a cooling jacket arranged about said double acting engine, and a connection between said boiler and said cooling jacket whereby said double acting engine is cooled by water at substantially boiler temperature.

3. A prime mover, according to claim 1, including in addition a boiler and a connection between said boiler and said double acting engine whereby the combustion gases of said double acting engine exhaust into the furnace of said boiler.

4. A prime mover according to claim 1, including in addition a condenser arranged to operate in conjunction with said turbine.

5. In a prime mover, according to claim 1, a condenser arranged to operate in conjunction with said turbine, a boiler, and a connection between said condenser and said boiler whereby the

condensate of said condenser may be reheated in said boiler.

6. A prime mover, according to claim 1, including in addition a boiler, a cooling jacket arranged about said double acting engine, a connection between said boiler and said cooling jacket whereby said double acting engine is cooled by water at substantially boiler temperature and a connection between said boiler and said double acting engine whereby the gases of combustion of said double acting engine exhaust into the furnace of said boiler.

7. A prime mover, according to claim 1, including in addition a boiler, a cooling jacket arranged about said double acting engine, a connection between said boiler and said cooling jacket whereby said double acting engine is cooled by water at substantially boiler temperature, and a condenser arranged to operate in conjunction with said turbine.

8. A prime mover, according to claim 1, including in addition a boiler, a cooling jacket arranged about said double acting engine, a connection between said boiler and said cooling jacket whereby said double acting engine is cooled by water at substantially boiler temperature, a condenser arranged to operate in conjunction with said turbine, and a connection between said condenser and said boiler, whereby the condensate of said condenser may be reheated in said boiler.

9. A prime mover, according to claim 1, including in addition a boiler, a connection between said boiler and said double acting engine whereby the combustion gases of said double acting engine exhaust into the furnace of said boiler and a condenser arranged to operate in conjunction with said turbine.

10. A prime mover, according to claim 1, including in addition a boiler, a connection between said boiler and said double acting engine whereby the combustion gases of said double acting engine exhaust into the furnace of said boiler, a condenser arranged to operate in conjunction with said turbine and a connection between the said condenser and said boiler, whereby the condensate of said condenser may be reheated in said boiler.

11. A prime mover, according to claim 1, including in addition a boiler, a cooling jacket arranged about said double acting engine, a connection between said boiler and said cooling jacket whereby said double acting engine is cooled by water at substantially boiler temperature, a connection between said boiler and said double acting engine whereby the combustion gases of said double acting engine exhaust into the furnace of said boiler and a condenser arranged to operate in conjunction with said turbine.

12. A prime mover, according to claim 1, including in addition a boiler, a cooling jacket arranged about said double acting engine, a connection between said boiler and said cooling jacket whereby said double acting engine is cooled by water at substantially boiler temperature, a connection between said boiler and said double acting engine whereby the combustion gases of said double acting engine exhaust into the furnace of said boiler, a condenser arranged to operate in conjunction with said turbine, and a connection between said condenser and said boiler, whereby the condensate of said condenser may be reheated in said boiler.
